APPARATUS FOR LAYING PLASTIC PIPE

Charles F. Blinne, P.O. Box 445,
Poplar Bluff, Mo. 63901

Filed Oct. 2, 1967, Ser. No. 8,810

Term of patent 14 years

(Cl. D39—1)

FIGURE 1 is a side elevational view of the apparatus for laying plastic pipe showing my new design;
FIG. 2 is a top plan view thereof;
FIG. 3 is a front elevational view thereof;
FIG. 4 is a rear elevational view thereof;
FIG. 5 is a vertical, cross-sectional view taken on irregular line 5—5 of FIG. 1; and

FIG. 6 is a vertical, cross-sectional view taken on line 6—6 of FIG. 1 showing the outer configuration of the apparatus for laying plastic pipe, portions of the internal components having been omitted for clarity.

I claim:
The ornamental design for an apparatus for laying plastic pipe, as shown and described.
